CLAIM

The ornamental design for a smartphone sterilizer, as shown and described.

DESCRIPTION

FIG. 1 is a perspective view of a front, top, and right side of a smartphone sterilizer;

FIG. 2 is a perspective view of a rear, bottom, and left side of the smartphone sterilizer of FIG. 1;

FIG. 3 is a front elevational view of the smartphone sterilizer of FIG. 1;

FIG. 4 is a rear elevational view of the smartphone sterilizer of FIG. 1;

FIG. 5 is a left side elevational view of the smartphone sterilizer of FIG. 1;

FIG. 6 is a right side elevational view of the smartphone sterilizer of FIG. 1;

FIG. 7 is a top plan view of the of the smartphone sterilizer of FIG. 1;

FIG. 8 is a bottom plan view of the smartphone sterilizer of FIG. 1; and,

FIG. 9 is an enlarged view of the encircled portion shown in FIG. 1.

The broken lines in the drawings are for the purpose of illustrating portions of the smartphone sterilizer that form no part of the claimed design.

1 Claim, 6 Drawing Sheets
